UNITED STATES PATENT OFFICE.

GEORGE C. DEBAY, OF CHESWICK, PENNSYLVANIA, ASSIGNOR OF ONE-HALF TO
GEORGE A. KOEHLER, OF CHESWICK, PENNSYLVANIA.

GLASS-MANIPULATING APPARATUS.

1,172,262.

Specification of Letters Patent. Patented Feb. 22, 1916.

Application filed January 30, 1915. Serial No. 5,265.

To all whom it may concern:

Be it known that I, GEORGE C. DEBAY, a citizen of the United States, and resident of Cheswick, in the county of Allegheny and 5 State of Pennsylvania, have invented a new and useful Improvement in Glass-Manipulating Apparatus; and I do hereby declare the following to be a full, clear, and exact description thereof.

10 My invention relates to glass-manipulating apparatus.

In the manufacture of window-glass, the glass is first formed in the form of cylinders, which are cut longitudinally and the cylinder is then opened out and flattened. This last operation has heretofore been performed by hand, and involved the employment of skilled labor, while, furthermore, the operation was a long and tedious one.

15 The object of my invention is to provide apparatus by means of which the opening out and flattening of these glass cylinders may be accomplished in such a manner as to greatly reduce the time and labor, while at 25 the same time the product will be of a standard and uniform character.

To these ends my invention comprises the novel features hereinafter set forth and claimed.

30 In the accompanying drawings, Figure 1 is a sectional plan view of a furnace with my apparatus installed therein; Fig. 2 is an enlarged front view of my improved apparatus with a portion of the furnace; Fig. 3 is a section on the line 3—3, Fig. 2; Fig. 4 is a section on the line 4—4, Fig. 2; Fig. 5 is a vertical section of the receiving chamber for the cylinder with the preliminary device in position therein; Fig. 6 is a front view of the 35 preliminary device; Fig. 7 is a section of the final flattening device; Fig. 8 is a sectional view of the preliminary device; and Fig. 9 is a front view of the handles of the preliminary device and the method of locking the 40 same together.

45 Referring to the drawings, I have illustrated my invention in connection with a furnace of circular form, with a series of carriages traveling on a track therein, each carriage carrying a flattening stone or plate.

The numeral 2 designates the outside circular wall of the furnace and 3 the inside circular wall, leaving the circular open space 4 at the center. Within the furnace is the 50 circular track 5 upon which the wheels 6 of

the carriage 7 travel. These carriages may be of any suitable construction, and said carriages carry the flattening stones 8 of the ordinary character. In order to drive the carriages 7, a rack-bar 9 is provided 60 which may be engaged by suitable power-driven cog-wheel for moving said carriages intermittently, as hereinafter set forth.

A vestibule 10 communicates with the furnace, said vestibule having the charging 65 opening 11 through which the glass cylinders are introduced. This vestibule 10 has the opening 12 which connects with the opening 13 of the furnace.

A pedestal 14 forms a support for the 70 casting 15. This casting has the projection 16 which fits into an opening in said pedestal. A washer 17 is interposed between said pedestal and said projection, and a screw 18 is threaded into said projection, whereby 75 said casting 15 is swiveled in said pedestal. The casting 15 has an opening 15^a extending through it to receive the outer end of the beam 19. The beam 19 has the opening 20 through which the pin 21 passes, said pin 80 being threaded into the casting 15 as clearly indicated in Fig. 5. To allow for slight tilting of the beam 19 the casting 15 is cut away at 22 and 23. The inner end of the beam 19 has the downwardly projecting 85 arm 24 provided with the roller 25 which moves on the track 26. This track 26, as indicated in Fig. 6 is at a lower level at one end as at 27 for the purpose more fully 90 hereinafter set forth.

95 Mounted on the beam 19 and slidable thereon are the bearings 28. These bearings have the lugs 29 to which are pivoted curved arms 30. Hinged or pivoted to the arms 30 are like curved arms 31 which are pivoted to the lugs 32 on the divided halves 33 of the spindle 34. At the outer end of each half of the spindle 34 are the handles 35. The latch 36 is adapted to lock the spindle in 100 closed position, as indicated in Fig. 9. At the outer end of the spindle 34 are the semi-circular members 37 which in their closed position are adapted to be inserted in the glass cylinder 38, and said members are preferably formed of spaced ribs 39 to provide 105 a light skeleton construction which can be easily manipulated by hand if desired.

Extending from the outside of the furnace to the inner space 4 are the channels 40. On the inner face of one of the channels 40 110

are the lugs 41 which form a bearing for the rock-shaft 42 extending from one end of the said channel to the other. A lever 43 is connected to the outer end of said shaft.

5 Arms 44 are rigidly mounted on said shaft, the opposite ends of said arms being connected to the bars 45 by a slot and pin connection 46, as clearly indicated in Fig. 2.

The bars 45 are connected at their ends to 10 the toggle-arms 47, the opposite ends of said toggle-arms being connected to the channels 40 and to the frames 48, which are slideable vertically in the guides 49. Rack-bars 50 are carried by frames 48. Divided pinions 15 51 are mounted on each end of the divided shaft 52. This shaft 52 also carries the flattening member 53 which consists of a divided cylinder, as illustrated in Fig. 7, the working faces of said cylinder presenting a 20 solid circular face, and formed of a suitable refractory material mounted on an inner shell 54. As clearly illustrated in Fig. 4, the shaft 52 passes through the openings 55 in the inner and outer furnace walls and 25 sufficient clearance is provided for the vertical movement of said shaft as will more fully hereinafter appear.

To provide for the oscillating movement of the flattening cylinder halves, I have 30 illustrated the following mechanism, although it is apparent that other forms of mechanism may be employed for accomplishing the same results. In this instance, I employ the lazy-tongs 56 one end of which 35 is connected to one of the pinion halves 51 and the other to the opposite one, as clearly indicated in Fig. 2. The lazy-tongs have the sleeves 57 which slide up and down on the guide-rod 58. The upper of the sleeves 40 57 is connected to the piston-rod 59 of the cylinder 60, which is carried by the frame 61. It will be apparent that by the reciprocation of the piston-rod 59 the pinion-halves 51 will oscillate back and forth on the rack 45 50, as indicated in Fig. 2, and this will cause a like oscillating movement of the halves of the flattening cylinder 53.

In practising my invention, the cylinder to be flattened having been slit longitudinally, 50 as indicated in Fig. 8, is inserted in the opening 11 of the vestibule 10 of the furnace and rests upon a suitable support. The operator then advances the spindle 34 by grasping the handles 35 and moves the semi-circular 55 halves 37 in their closed position into the cylinder in the vestibule 10, as indicated by dotted lines Fig. 1. The spindle is then swivelled around and with it the beam 19 with the roller 25 traveling on the track 26, until 60 the cylinder is swivelled from the vestibule 10 over into the main part of the furnace onto one of the stones 8 of one of the carriages 7 which is in position to receive it. During 65 this swinging operation the cylinder is lifted slightly from the floor of the vestibule 10 so

as not to drag thereon, due to the fact that the track 27 is slightly raised, and when the cylinder has been swung around into position where the cylinder is supported on one of the carriages 7, the wheel 25 travels down the lower section 27 of the track and brings the cylinder down into contact with the flattening stone of the carriage. When this has been done the parts assume the position indicated in full lines Fig. 1, and the operator now unlocks the handles 35 by throwing back the latch 36, whereupon by separating the handles the halves of the spindle 34 as well as the halves 37 of the preliminary opening member assumes the positions indicated in dotted lines Fig. 8, so that the glass cylinder is opened out on the stone 8. This operation is repeated by moving the handles back and forth to get the oscillating movement and when the glass has been opened out to the proper extent, the operator withdraws the spindle from the furnace, and swings it around in position with reference to the vestibule 10 to be inserted in a fresh cylinder which has been charged through the opening 11. Power is now applied to move the carriages 7 in the furnace, and the carriage carrying the glass, which has just been opened, is moved around into position for flattening, where the carriage is stopped and the flattening operation takes place. In order to raise the flattening cylinder 53 sufficiently to permit the plate to pass under it, the operator moves the lever 43 and through the arms 44 the bars 45 and the toggle-arms 47 the frame 48 is lifted and with it the pinions 51 and the flattening cylinders 53. This permits the glass to pass under the cylinder, whereupon the lever 43 is moved to lower the flattening cylinder onto the glass. Power is now applied to the cylinder 60 to reciprocate the piston-rod 59 and through the connections described, an oscillating movement is imparted to the halves of the flattening cylinder 53 so that they move over the surface of the glass on the flattening stone and flatten it out and smooth it at the same time. This operation is continued until the glass has been flattened, whereupon, power is applied to move the carriages and the flattened plate is moved beyond the flattening roll, while another plate previously opened, is brought into position to be flattened.

In the claims I wish to claim broadly the cylindrical member divided longitudinally into two parts, whether used as a preliminary opener like the cylinder 37, or whether used for the final flattening operation like the cylinder 53. It is possible that the opening and flattening may be done entirely by one cylinder.

What I claim is:

1. A device of the character described, comprising a member divided longitudinally,

and having two curved rocking working faces.

2. A device of the character described, comprising a cylindrical member divided longitudinally into two rocking parts.

3. A device of the character described, comprising a member divided longitudinally into two parts having curved working faces, and means for rocking said parts on their curved faces.

4. A device of the character described, comprising a longitudinally divided spindle or shaft, having curved working faces on each half, and means for rocking said halves on their curved faces.

5. A device of the character described, comprising a longitudinally divided shaft having curved working faces, means for rocking said shaft halves on their curved faces, and means for elevating said shaft.

6. In apparatus of the character described, comprising a longitudinally divided shaft having curved working faces, pinion-sections carried by said shaft-sections, a rack bar en-

gaged by said pinion-sections, and means for oscillating said pinion-sections.

7. In apparatus of the character described, comprising a longitudinally divided shaft having curved working faces, pinion-sections carried by said shaft-sections, a rack-bar engaged by said pinion-sections, a power operated cylinder, and connections between said cylinder and said pinion-sections for oscillating same.

8. In apparatus of the character described, comprising a longitudinally divided shaft having curved working faces, pinion-sections carried by said shaft, a rack engaged by said pinion-section, lazy tongs engaged by said pinion-sections, and means for operating said lazy-tongs.

In testimony whereof, I, the said GEORGE C. DEBAY, have hereunto set my hand.

GEORGE C. DEBAY.
